STRATIFIER BELT ASSEMBLY

This invention relates to a conveyor belt assembly.

Conveyor belts having various classifying means built therein have been employed for classifying grain, sand, gravel, and the like. The classifying means is usually fabricated integrally into the structure of the belt. This type of construction has at least two serious disadvantages. First, the belt must be shut down periodically for cleaning. Secondly, when the integrally formed classifying means becomes worn, the entire belt must be discarded. It would be desirable to have a classifying conveyor belt provided with a replaceable classifying means which can be (a) readily cleaned while in operation and (b) readily replaced when worn, i.e., replaced without having to discard the entire belt. The present invention provides such a classifying conveyor belt.

An object of this invention is to provide an improved classifying conveyor belt. Another object of this invention is to provide a classifying conveyor belt having a replaceable classifying means. Another object of this invention is to provide a classifying conveyor belt which can be readily cleaned while in operation. Another object of this invention is to provide a classifying conveyor belt which is provided with a removable classifying means formed of a semirigid solid plastic material. Other aspects, objects, and advantages of the invention will be apparent to those skilled in the art in view of this disclosure.

Thus, according to the invention, there is provided a conveyor belt assembly comprising: an elongated base providing a generally flat mounting surface; a carrying cover mounted on said surface of said base; and a plurality of spaced apart, transversely extending, alternating ridges and valleys formed in said cover.

The carrying cover or replaceable classifying means in the belt of the invention is preferably formed of a semirigid solid plastic material. Such materials which can be employed in the practice of the invention include polyethylene, polypropylene, copolymers of ethylene or propylene with another 1-olefin, e.g., butene-1, polyvinylchloride, polytetrafluoroethylene, nylon, and the like. Particularly applicable for use in the present invention are the polymers of ethylene, propylene, or other 1-olefins prepared in accordance with the method of U.S. Pat. No. 2,825,721, J. P. Hogan et al. As used herein and in the claims, unless otherwise specified, the word "polymer" is employed generically and includes both homopolymers and copolymers.

FIG. 1 is a view in elevation of a conveyor belt assembly in accordance with the invention.

FIG. 2 and FIG. 3 are plan views of conveyor belt assemblies in accordance with the invention.

FIG. 4 is a perspective view, partly in cross section, of another conveyor belt assembly in accordance with the invention.

FIG. 5 is a diagrammatic view illustrating one assembly of apparatus in which the conveyor belt of the invention can be employed.

FIG. 6 is a cross-sectional view of the plastic hinge employed with the invention.

Referring now to the drawings, wherein like reference numerals have been employed to denote like elements, the invention will be more fully explained. In FIG. 1 there is illustrated a conveyor belt assembly comprising an elongated base belt 12 having a generally flat upper mounting surface 14. A carrying cover 16, preferably formed of a semirigid solid plastic material, is mounted on said surface 14 of said base belt 12. Any suitable means can be employed for mounting said carrying cover on said base belt. One presently preferred means comprises employing rivets 18, as at the overlapping ends of sections of the carrying cover, and also at intermediate points of the carrying cover, both as illustrated in said FIG. 1. Said carrying cover 16 has formed therein a plurality of spaced apart, transversely extending, alternating ridges and valleys, as illustrated in FIG. 1.

Said alternating ridges and valleys can be formed in any suitable or convenient manner. One presently preferred method of forming said alternating ridges and valleys com-

prises forming a plurality of hinges which extend transversely across a sheet or web of a semirigid plastic material, and then compressing said sheet or web longitudinally to cause bending thereof and thereby form said valleys and ridges.

Such hinges can be formed merely by flexing of the semirigid plastic material, which flexing causes molecular orientation in the line of the flexing. It is frequently preferred, however, to thin the sheet or web of plastic material along the proposed hinge line. This can be done by heating either the plastic material, or a bar or roller, to just below the softening point of the plastic material, and either pressing or rolling said plastic material to thin same along the line of the proposed hinge. The plastic material is then flexed along the line of pressing or rolling. The hinge can alternately be formed by machining a groove in the plastic material with conventional wood or metal tools. Tool speed should be controlled so that excessive frictional heat is not generated in cutting the hinge line. Again, the hinge is formed by flexing the plastic material along the cut hinge line. Another method of forming the hinge comprises cold working the plastic material by passing a sheet thereof between two rollers so as to reduce the cross section of the plastic material along the desired hinge line. When the hinge is formed by flexing only, the flexing appears to reorient the plastic material to produce a necked-down cross section which will be in the range of from 75 to 90 percent of the original cross section. For example, a $\frac{1}{8}$ -inch thick sheet will be necked down from both sides to leave a cross section approximately one-tenth of an inch in thickness with the necked-down length being from one-eighth to one-fourth of an inch. When the hinge is formed by prethinning the plastic material along a given line and then flexing same, the hinge itself can be from 10 to 15 mils thick, and the hinge width can be between 30 and 60 mils. In such instances, the thickness will decrease slightly after the first flexing of the hinge due to "neck-down" of the plastic. Thus, at least two similar methods are available for forming said hinges. The "necked-down" portion of the hinge is illustrated at 38 in FIG. 6. The width of the hinge is considered to be the distance between A and B.

The above methods of forming hinges in semirigid solid plastic materials are known in the art and form no part of the instant invention. It is known that hinges formed in various thermoplastic materials by the methods described above have exceptional flexlife characteristics. Polypropylene hinges, for example, formed by the methods described above, have withstood over a million flex cycles without failure.

The carrying cover in the belt assemblies of the invention can be fabricated from sheets of semirigid solid plastic material having any suitable thickness. It is presently preferred to use sheets having a thickness within the range of about one-sixteenth to about one-fourth inch.

The number and size of the alternating ridges and valleys formed in the carrying cover will depend upon the manner in which the belt assembly is employed and the material being classified. While the invention is not limited in this respect, generally speaking, the valleys will have a depth within the range of from about one-sixteenth to about 2 inches measured vertically from the bottom of the valley, and the number of ridges will be within the range of from about four per inch to about three per foot.

Preferably, the carrying cover will comprise a plurality of separate cover sheets connected to each other at adjoining ends thereof, e.g., as in FIG. 1. Said cover sheets can be of any suitable length, depending upon the overall length of the carrying cover. Said cover sheets will usually range from about 2 to about 6 feet in length. However, it is within the scope of the invention to form the carrying cover of one cover sheet joined at the ends thereof so as to provide a continuous cover for the base belt.

Said carrying cover can have any suitable width ranging from less than the width of the base belt as shown in FIG. 2, to greater than the width of the base belt, as shown in FIG. 3. It is generally preferred that said carrying cover have substantially the same as or slightly less width than the width of the base

belt. Said base belt can be formed of any suitable conventional belting material, such as laminated rubber, canvas, or rubber-coated canvas, etc., Said base belt can have any suitable width, depending upon the service it is employed in. Usually said belt will range from 2 to 6 feet in width. Said base belt and associated carrying cover can have any convenient overall length, e.g., 10 to 20 feet, depending upon the service of the belt.

FIG. 4 illustrates one presently preferred belt assembly in accordance with the invention. In FIG. 4 the base belt 12' is provided with an upwardly extending flange 20 at each side edge thereof. The height of said side edge flanges can range from about one-sixteenth inch to 2 inches. Generally speaking, it is preferred that the height of the alternating ridges in the carrying cover employed with the flanged base belt of FIG. 4 be about the same height as the height of said flanges 20. However, it is within the scope of the invention for the height of said ridges to be less than or greater than the height of said flanges 20.

As indicated above, the classifying belts of the invention can be employed in classifying and/or concentrating a wide variety of materials. Generally speaking, any divided or particulate material having a specific gravity greater than one can be concentrated using the belt assemblies of the invention. Said belts of the invention are particularly useful in classifying and/or concentrating mineral ores. The belts of the invention are especially suitable in the concentration and recovery of gold. In such use said belts are suitable for the recovery of fine gold, coarse gold, or both together, and can be used on a feed stream as coarse as 10 mesh or as fine as 200 mesh, or finer. The pulp density of the slurry feed to the belt will vary, depending upon the type of previous milling treatment, but will usually run about 20 percent solids.

FIG. 5 illustrates diagrammatically one type of apparatus which can be employed in the concentration of gold when using the belt assembly of the invention. In FIG. 5 a belt assembly 10 is disposed around support rollers 22 and 24, of which roller 22 is the drive roller and is driven by means of motor 26 and the drive belt shown. The slope of said belt is usually fixed for a given machine and can range from about one-fourth to about 3 inches per foot, depending upon the particular service in which the machine is being employed. The belt speed is adjustable and can range from about 30 to 150 inches per minute. Belt speed is usually adjusted to slope and feed pulp density. In operation, a slurry or pulp of the mineral to be recovered is discharged from feed sole 28 onto the surface of the belt 10. A stream of water is introduced onto said belt from conduit 30. The gold or other heavy mineral which settles on the belt and is collected in the valleys therein is dragged up beyond the outlet of feed sole 28 where it is contacted with the water from conduit 30 which flows downslope along the belt. As the belt is rotated around roller 22, the material collected in the valleys of belt 10 is contacted with a second stream of water from conduit 32 and washed onto the surface of conveyor 34. Said conveyor 34 conveys the concentrated gold or other mineral to further processing steps. The tailings and other lighter material which do not settle in the valleys on belt 10 are carried down the surface of the belt by the downflowing stream of water and deposited in a tailings box 36 which is disposed below and beyond roller 24. While not shown in the drawing, it is within the scope of the invention to employ the belt of the invention on machines similar to that illustrated in FIG. 5 which are also provided with means for shaking the belt.

A number of advantages are realized when employing the belt assemblies of the invention. One outstanding advantage is that the carrying cover of the belt assembly can be readily

cleaned. The surface of the plastic materials used in fabricating said carrying covers is virtually self-cleaning. Minerals, metals, and tailing materials associated therewith do not adhere to the surface of the carrying cover. All of said materials are easily removed by spraying with water. This is also advantageous in that the heavy material which is concentrated in the valleys of the carrying cover is readily removed therefrom without the necessity of a doctor blade. Another advantage is the long life of the carrying cover. Said plastic materials are remarkably wear-resistant. Still another advantage is the low cost of the plastic material. Still another advantage is the ease of fabrication and replacement of the carrying covers, when such replacement does infrequently become necessary. When the carrying cover is fabricated from a plurality of cover sheets, still another advantage is obtained in that individual cover sheets can be replaced without having to replace the entire carrying cover. If the carrying cover should become damaged, it can be repaired without difficulty by heat sealing, fusion, or by the use of epoxy adhesives.

While certain embodiments of the invention have been described for illustrative purposes, the invention is not limited thereto. Various other modifications of the invention will be apparent to those skilled in the art in view of this disclosure. Such modifications are within the spirit and scope of the disclosure.

I claim:

1. A classifier comprising: an inclined endless elongated base belt providing a generally flat mounting surface; a semirigid carrying cover removably mounted on said surface of said base; and a plurality of spaced apart, transversely extending, self-sustaining alternating ridges and valleys integrally formed in said cover when it is mounted on said base, means for driving said belt; and means for feeding material to be classified onto said belt.
2. A belt according to claim 1 wherein said cover is formed of a semirigid solid plastic material.
3. A belt according to claim 2 wherein said plastic material is a polymer of ethylene or a polymer of propylene.
4. A belt according to claim 1 wherein: said cover comprises a semirigid sheet of solid plastic material having a plurality of spaced apart flexible hinges formed therein, said sheet being compressed longitudinally to cause bending thereof at said hinges to form said self-sustaining ridges and valleys when said sheet is mounted on and fixed to said base belt.
5. A conveyor belt according to claim 4 wherein: said cover comprises a plurality of cover sheets, connected to each other at adjoining ends thereof, and fixed to said base; and a plurality of said alternating ridges and valleys are formed in and extend transversely across each of said cover sheets.
6. A conveyor belt according to claim 5 wherein said plastic material is polypropylene.
7. A classifier according to claim 1 wherein: said base belt is provided with an upwardly extending flange at each side edge thereof; said cover comprises a plurality of cover sheets, connected to each other at adjoining ends thereof, and mounted on said surface of said base belt between said flanges; and a plurality of said alternating ridges and valleys are formed in and extend transversely across each of said cover sheets.
8. A classifier according to claim 7 wherein: said cover sheets are formed from a semirigid sheet of solid plastic material; said alternating ridges and valleys comprise a plurality of spaced apart flexible integral hinges formed in each said cover sheet; and each said cover sheet is compressed longitudinally to cause bending thereof at said hinges and form said ridges and valleys.
9. A classifier according to claim 8 wherein said plastic material is polypropylene.
